US0D1028946S

(12) **United States Design Patent** (10) **Patent No.:** **US D1,028,946 S**
(45) **Date of Patent:** **** May 28, 2024**

(54) **EARPHONE**

(71) Applicant: **BEIJING XIAOMI MOBILE SOFTWARE CO., LTD.**, Beijing (CN)

(72) Inventor: **Hongyu Chen**, Beijing (CN)

(73) Assignee: **BEIJING XIAOMI MOBILE SOFTWARE CO., LTD.**, Beijing (CN)

(**) Term: **15 Years**

(21) Appl. No.: **29/914,911**

(22) Filed: **Oct. 23, 2023**

Related U.S. Application Data

(62) Division of application No. 35/515,218, filed on Mar. 17, 2022 (U.S. filing date under 35 U.S.C. 384), and having an international filing date of Mar. 17, 2022, now Pat. No. Des. 1,007,480.

(30) **Foreign Application Priority Data**

CLAIM

The ornamental design for an earphone, as shown and described.

DESCRIPTION

FIG. 1 is a front view of an earphone showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a bottom perspective view thereof.

The broken lines shown in the drawings illustrate portions of the earphone and form no part of the claimed design.

1 Claim, 8 Drawing Sheets
